UNITED STATES PATENT OFFICE.

FARNUM F. DORSEY, OF NEW YORK, N. Y., ASSIGNOR TO BENJAMIN PHILLIPS, OF LYNN, MASSACHUSETTS.

SHUTTLE-THREAD-REPLENISHING MECHANISM.

1,077,056.

Specification of Letters Patent. Patented Oct. 28, 1913.

Application filed June 15, 1907. Serial No. 379,263.

To all whom it may concern:

Be it known that I, FARNUM F. DORSEY, a citizen of the United States, residing at New York, in the county of New York and State of New York, have invented certain new and useful Improvements in Shuttle-Thread-Replenishing Mechanism; and I do hereby declare the following to be a full, clear, and exact description of the invention, such as will enable others skilled in the art to which it appertains to make and use the same.

The present invention relates to sewing machines and more especially to lock stitch sewing machines such as are adapted for use in the manufacture of boots and shoes.

In this type of machine during each stitch forming operation the thread supply from which the locking thread is drawn passes through a loop of thread drawn through the work by the needle and the locking thread supply can therefore contain but a limited quantity of thread. Consequently it is necessary to frequently suspend the operation of the machine in order to replenish the supply of thread in the shuttle or other device which contains the locking thread supply with a resulting loss of time and a reduction in the production of the machine.

The replenishing of the supply of thread in the shuttle or thread-holder when the supply becomes exhausted has heretofore been performed by the operator who manually removes the empty thread bobbin and introduces a full bobbin into the shuttle or thread-holder. In accordance with the principal feature of the present invention the inconvenience and loss of time incident to the replenishing of the supply of thread in the thread-holder by the operator in the usual manner is eliminated by providing mechanism which operates to automatically introduce a supply of thread into the thread-holder. In case the locking thread supply is carried upon a thread bobbin as is usual, the loss of time incident to the replenishing of the thread supply may be further reduced by also providing mechanism for automatically removing the empty bobbin from the thread-holder and the provision of such mechanisms constitutes a further feature of the invention.

The provision of mechanism for replenishing the supply of thread in the thread-holder not only results in a reduction in the loss of time incident to the performance of

this operation and a consequent increase in the production of the machine, but also enables a reduction in the size of the thread-holder. This is rendered practicable by reason of the facility with which the thread supply is replenished when exhausted and results in diminishing the length of the loop of needle thread which must be drawn through the work and passed around the thread-holder. Consequently there is less rendering of the thread back and forth through the work and about the thread-handling devices of the stitch-forming mechanism and less wear upon and weakening of the thread.

When a supply of thread is introduced into the thread-holder the end of this thread must be threaded through a tension device and a sufficient length of thread drawn off from the thread supply to reach the work and be sewed into the seam, and certain features of the invention contemplate the employment of devices for automatically performing these operations.

In accordance with the broader features of the invention the means for passing a loop of the needle thread about the holder which carries the thread supply from which the locking thread is drawn may be of any suitable or well known construction, and the passing of the loop of needle thread about the holder may be effected by a movement of either the loop of thread or of the thread holder or of both. The introduction of the thread supply into the holder may also be effected in any suitable manner although it is preferred to carry the thread supply upon a thread bobbin and to replenish the supply of thread in the holder by removing an empty bobbin from the holder and replacing it with a full bobbin.

In embodying the broader features of the invention in a concrete construction I have devised certain further features of invention which, while they are not essential to the broader features of the invention, are of importance in contributing to the simplicity and efficiency of the machine.

The various features of the invention will be understood from an inspection of the accompanying drawings and from the following detailed description of the construction shown therein.

In these drawings, Figure 1 is a front elevation of a part of a sewing machine em-

bodying the features of the present invention in their preferred form; Fig. 2 is a plan view; Fig. 3 is a sectional elevation through the axis of the shuttle, looking from right to left; Fig. 4 is a similar view showing in detail and partly in section the starting and stopping mechanism; Fig. 5 is a detail front view of the shuttle and adjacent parts; Fig. 6 is a detail plan view of the bobbin case and tension device; Figs. 7, 8 and 9 are detail views illustrating successive steps in the operation of changing the bobbin; Fig. 10 is a detail plan view of the bobbin feeding gates and their actuating mechanism.

In the drawings the invention is illustrated as embodied in a lock-stitch sewing machine of the type used in stitching together the outer sole and welt of a welted shoe, and as the stitch-forming instrumentalities of such a machine are well known, only so much of the machine is shown as relates to the present invention, the needle, awl, take-up and other usual instrumentalities being omitted as they may be of any usual or suitable form.

In the machine shown in the drawings the means for passing a loop of needle thread about the locking thread supply is 30 a rotary discoidal shuttle and the locking thread supply is replenished when exhausted by removing an emptied thread bobbin from a thread holder mounted within the shuttle and substitute a full thread bobbin therefor, these operations being performed automatically under the control of the operator.

The shuttle indicated at 1 is mounted to rotate in a shuttle race or casing 2 and is 40 actuated by projections 3 on the rotating shuttle driver 4. The shank 5 of the shuttle driver is journaled in a bearing 6 and the shuttle driver is rotated through a pinion 7 fixed to the shank and meshing with 45 a pinion 8. The pinion 8 is secured to a shaft which is driven from the driving shaft 11 of the machine by a bevel gear 10 fixed to the driving shaft and engaging a bevel pinion 9 secured to the end of the 50 shaft which carries the pinion 8. (Figs. 2 and 3.)

The shuttle is provided with a concentric recess within which a bobbin holder 13 is loosely mounted so that the shuttle may 55 rotate freely about the holder which is held from rotation by devices to be hereinafter described. The bobbin holder is provided with a concentric stud 14 upon which the thread bobbin 15 is journaled and the bobbin holder and shuttle are provided with openings in their rear sides through which the thread bobbin may be introduced into the bobbin holder within the shuttle. The shuttle driver is provided with a recess 16 65 equal in diameter to the diameter of the

thread bobbin and arranged in line with the openings through the rear of the bobbin holder and shuttle. This recess 16 is provided with lateral openings 17 and 18 constituting respectively an outlet through which empty bobbins may be discharged and an inlet through which full bobbins may be introduced into the recess 16. When a bobbin is to be introduced into the bobbin holder, the rotation of the shuttle and driver is arrested with the opening 18 in register with the lower end of a vertical chute 19 in which a series of full bobbins are supported. The series of bobbins in the chute 19 are normally supported upon a gate 21. When a bobbin is to be introduced the gate 21 is withdrawn from the chute and at the same time a second gate 22 is moved forward between the lower bobbin and the next bobbin in the chute so that the lower bobbin is separated from the series of bobbins in the chute and allowed to drop into the recess 16.

The insertion of the bobbins into the bobbin holder and the removal of the emptied bobbins therefrom is effected by a plunger 23 mounted concentrically in the shank of the shuttle driver as indicated in Fig. 3. When a bobbin is to be introduced the plunger 23 is retracted so that the bobbin may be dropped from the chute 19 into the recess 16 in front of the plunger. The plunger then advances carrying the bobbin forward into the bobbin holder. In order that the plunger may also act to remove an emptied bobbin when it is ejected from the bobbin holder, the plunger is forked at its forward end so as to provide two resilient prongs 24 which are bent slightly away from each other and are beveled at 25 on their forward extremities. When an emptied bobbin is to be removed the plunger is advanced to bring the bevel ends 25 of the prongs into the opening in the center of the bobbin and then the bobbin is forced out of the bobbin holder and on to the end of the plunger. The plunger is then retracted carrying the emptied bobbin with it until the bobbin strikes against the rear end of the recess 16 when the continued movement of the plunger withdraws it 110 from the bobbin so that the bobbin may drop through the opening 17.

After a full bobbin has been inserted in the bobbin holder it is necessary to draw the end of the thread carried by the bobbin into engagement with the tension device through which the thread leads to the seam. One member of this tension device consists of a nose 27 projecting from the front face of the bobbin holder as shown in Figs. 5 and 6. 120 The other member of the tension device consists of a tension spring, the lower end 28 of which is arranged to engage the thread and press it against the nose 27. This spring is provided with a curved shank 29. 130

which fits within a recess formed in the periphery of the bobbin holder. The spring is adjustably secured in the recess by a screw 31 which passes through a slot 32 in the shank of the spring. The lower end of the tension spring projects forward through an opening 30 in the front of the bobbin holder. (Fig. 5). The pressure of the spring against the thread may be adjusted by a screw 33 which engages the end of the shank 29 and by which the spring may be moved circumferentially on the bobbin holder. This arrangement and construction of the tension device enables the thread to be inserted therein by a simple forward and downward movement and with or without the assistance of a device arranged to enter between the thread nose and tension spring to separate them as the thread is introduced.

The bobbin holder is held from rotation during the operation of the machine by a retaining device 35 which embraces the thread nose 27 and tension spring 28. This retainer is mounted upon an arm 36 which also carries a device 37 arranged to enter between the members of the tension device and separate them when the end of the bobbin thread is to be carried between said members. (Fig. 5).

In case the end of the bobbin thread is to be drawn into the tension device by automatic devices, it should be presented in the same position whenever a full bobbin is introduced into the bobbin holder. To insure the proper positioning of the end of the bobbin thread, the forward flange 38 of the bobbin is provided with recesses forming vertical shoulders 39 (Fig. 5) and the chute 19 is provided with vertical guides 40 (Figs. 2 and 10) arranged to engage the shoulders, so that each bobbin is delivered into the recess 16 in the shuttle driver in the same relative position. The end of the bobbin thread is inserted at the time of filling the bobbin in a notch 41 formed in the flange 38 of the bobbin. This notch is made narrow enough to hold the thread securely and about 1/16th of an inch of the thread is allowed to project from the notch to permit the seizing of the end of the thread by the thread pulling grippers to be described. A vertical groove 42 (Fig. 2) is formed in the chute 19 to accommodate this projecting end of the bobbin thread.

When the bobbin is introduced into the bobbin holder the end of the thread projecting from the notch 41 is presented in position to be engaged and seized by the jaws of a thread puller 43. This thread puller comprises two arms 44 and 45 which are pivoted together at 46, the lower end of the arm 44 forming the fixed jaw of the gripper and the lower end of the arm 45 forming the movable jaw of the gripper. These lower gripping ends of the arms 44 and 45 are

formed as slender curved fingers 48 which are adapted to enter an opening 49 in the face of the bobbin holder and seize the end of the bobbin thread between them. The arm 44 of the thread puller is mounted on a shaft 17 (Fig. 1) which is rocked at proper intervals to move the lower end of the arms 44 and 45 toward or away from the bobbin holder.

The arm 36 which carries the bobbin holder 35 and the tension opener 37, and also the shaft 47 which carries the thread puller, are mounted upon a sleeve 55 which is arranged to slide vertically on the bobbin chute 19 and which is operated by mechanism to be described to impart vertical movements to the thread puller device, to the retainer for the bobbin holder, and to the tension opener.

When the supply of thread within the bobbin holder is to be replenished the machine is stopped with the shuttle driver in a position indicated in Fig. 3 and the mechanism which operates the devices for removing and inserting the bobbins and for passing the bobbin thread through the tension device and drawing off the proper length of thread is thrown into operation by the operator. When this mechanism is thus set into operation the plunger 23 is advanced to the position indicated in Fig. 7 and the fingers 48 of the thread puller are at the same time advanced so that they engage the front of the empty bobbin and push it back upon the prongs of the plunger as indicated in said figure. The plunger then retreats to its extreme rearward position so as to carry the empty bobbin against the rear end of the recess 16 and to withdraw from the bobbin which falls through the outlet opening 17. After the empty bobbin has passed from beneath the opening 18 at the bottom of the feed chute 19, the gates 21 and 22 act to deliver a full bobbin through the opening 18 into the recess 16 and in front of the retracted plunger 23. The plunger then moves forward again and pushes the full bobbin into the bobbin holder while the fingers 48 of the thread puller move back to the position indicated in Fig. 8, the fingers being separated slightly so that the end of the thread projecting through the notch 41 enters between the fingers. The fingers are then closed to seize the thread and a short downward movement is imparted to the fingers to free the thread from the notch 41. The thread gripping fingers then move downward and outward to carry the thread between the members of the tension device. At the same time the tension opener 37 is advanced between the thread nose and the tension spring above the thread and spreads them apart so that the tension device does not resist the free movement of the thread under the pull exerted by the thread puller.

An outward movement is then given to the thread puller to draw out slack thread as shown in Fig. 9 to provide enough thread to extend to the work and start the seam. 5 During this last movement of the thread puller the rounded lower extremity of the tension opener 37 acts as a guide or fulcrum about which the thread is drawn. The gripping fingers of the thread puller then release 10 the end of the thread and the puller returns to its original position. At the same time the tension opener 37 returns to the position indicated in Fig. 5 thus releasing the tension spring so that the thread is gripped between the members of the tension device. The retainer 35 for the bobbin holder also returns to normal position where it embraces the thread nose 27 and tension spring 28 and prevents rotation of the bobbin holder. The plunger 23 also retreats 15 slightly to clear the shuttle.

The movements above described are imparted to the bobbin changing device by a group of cams indicated generally by the reference character 51. These cams are secured together and are journaled on a sleeve 52 fixed in one of the uprights 53 in which the shaft 11 is mounted, and forming a bearing for the shaft, so that the cams 51 are mounted concentrically with but independently of the shaft.

The sleeve 55 on which the thread puller, the retainer for the bobbin holder, and the tension opener are carried, is moved vertically to give the required vertical movements to these parts by a cam groove formed in the face of the gear 64 through which the cam group 51 is driven. This cam groove is engaged by a cam roller 63 carried by an arm 62 which is secured to a rock shaft 59. The rock shaft is journaled at one end in a portion of the frame which is omitted from the drawings, and at the other end in a bracket 61 on the upright 53. An arm 58 is secured to this rock shaft, and is provided at its outer end with an adjustable pin 57 which engages two lugs 56 formed on the rear side of the sleeve 55.

The inward and outward swinging movements of the thread puller arms 44 and 45 are produced by a cam 70 in the cam group 51. This cam is engaged by an arm 69 fixed to one end of a sleeve 68 which is journaled on the shaft 59 (Fig. 2). A second arm 67 is fixed to the opposite end of the sleeve 68, and is connected by a link 66 with an arm 65 which is secured to the shaft 47 which carries the thread puller arms. A spring 71 surrounding the link 66 and engaging a lug 72 on the slide sleeve 55 keeps the arm 59 in contact with the cam 70.

The opening and closing of the gripper fingers of the thread puller are effected by a cam 83 of the cam group 51. This cam is engaged by an arm 82 secured to one end of

a sleeve 81 which is journaled on the sleeve 68 above referred to (Figs. 2 and 3). A second arm 80 is secured to the other end of the sleeve 81, and is connected by a link 79 with one arm 78 of a lever which is pivoted at 76 to a lug 77 on the slide sleeve 55. The other end 75 of this lever engages the upper end of the arm 45 of the thread puller. A grasshopper spring 73 is mounted between the arms 44 and 45 of the thread puller, and tends to hold the gripping fingers 48 of the thread puller together.

The plunger 23 is fixed to a slide 85 which is guided in ways 86 on the frame of the machine, and this slide is operated to impart the proper longitudinal movements to the plunger by a cam groove 95 formed in the side of the cam 83 above referred to. The slide 85 is provided with a roller 87 which is engaged by the forked end of an arm 88 which is offset at 89 (Fig. 10) and is fixed to one end of the sleeve 90 journaled on the sleeve 81 above referred to. A second arm 91 is fixed to the other end of the sleeve, and is pivoted to a link 92. The link is provided with a looped extremity 93 formed to slide on the sleeve 52 and is provided with a cam roll 94 which engages the cam path 95.

The gates 21 and 22 which act to separate individual bobbins from the series of bobbins in the chute 19, and deliver them in front of the plunger 23, are advanced and retracted at proper intervals by a slide 97 (Figs. 1 and 10) which is mounted to move between the outer ends of the gates, and is provided with inclined cam slots 101 and 102. The cam slot 101 is engaged by a pin 103 projecting from the gate 22, while the cam slot 102 is engaged by a similar pin 103 projecting from the gate 21. The slide 97 is moved backward and forward by the movements of the arm 88 which operates the plunger 23. The slide is connected to the arm 88 by means of a link 104, one end of which is connected with the slide, and the other end of which is pivoted to the arm 88 at 105. The cam slots 101 and 102 are so arranged that when the plunger 23 is moved backward the cam slots act to advance the upper gate so as to retain the column of bobbins and retract the lower gate so as to release the lowermost bobbin. When the plunger advances the cam slots act to move the gates in the reverse direction, advancing the gate 21 and retracting the gate 22, so that the lowermost bobbin is supported upon the gate 21 in position to be released upon the next operation of the gate. The forward ends of the gates may be beveled as indicated at 106 (Fig. 10) to facilitate their entrance between the bobbins.

In the construction shown, the stitch forming mechanism and the mechanism for

replenishing the supply of thread in the thread holding device are actuated by the same driver, which may be connected either with the stitch forming mechanism or with the mechanism for replenishing the thread supply at the will of the operator.

As shown, the driver consists of a pulley 109 provided with a driving plate 110. The pulley and driving plate are journaled to turn freely upon a sleeve 107 which is fixed to the end of the main shaft 11 of the machine, and forms an extension of said shaft. The sleeve 107 is provided with a friction plate 111 arranged upon one side of the driving plate 110 and adapted to be frictionally engaged and driven thereby. A second friction plate 112 is arranged on the opposite side of the driving plate 110, and is loosely journaled upon the projecting end 113 of the sleeve 52 on which the group of cams 51 which operate the thread replenishing mechanism is mounted. A pinion 114 is fixed to the hub of the plate 112, and engages a gear 115 which is secured on one end to a shaft 116 journaled in the column 53. A pinion 117 is fixed to the other end of the shaft 116, and engages the gear 64 which is connected with and forms a part of the cam group 51. When the driving plate 110 is in engagement with the friction plate 112 it operates to frictionally drive the plate 112 and through it and the connecting gear to drive the cam group 51 which operates the thread replenishing mechanism.

The driving pulley 109 is normally maintained in position with the driving plate 110 midway between the friction plates 111 and 112. The pulley is maintained in this position against the tension of the spring 122 which tends to force the pulley toward the left in Fig. 1, and to maintain the driving plate 110 in frictional engagement with the friction plate 111. The pulley and driving plate are moved and held against the tension of the spring 122 by means of a rod 119 which slides in a central recess in the main shaft 11, and is provided with fixed collars arranged to engage opposite sides of a plate 121 fixed to the end of the hub 108 of the pulley. The longitudinal movements of the rod 119 which result in the engagement of the driving plate 110 with either of the friction plates 111 or 112, or the movement of said driving plate into mid-position between said friction plates, are controlled or effected by a forked wedge 127 arranged between a collar 123 which is connected with the rod 119, and an inclined collar 126 which is formed on the end of the sleeve 52 (Figs. 1 and 2). The collar 123 is mounted on the shaft 11, and is connected with the rod 119 by means of a cross-pin 124 which passes through the collar, and rod and through slots 125 in

the shaft 11. When the forked wedge 127 is in the position indicated in Fig. 1 it maintains the pulley and driving plate in mid-position so that neither the sewing mechanism nor the thread replenishing mechanism is operated. The forked wedge 70 is fixed to the upper end of a rod 128, and is maintained in the position indicated in Fig. 1 by an arm 129 which projects rearwardly from a sleeve 130 and supports the lower end of the rod. The sleeve 130 is loosely journaled on a rock shaft 131 which is mounted in lugs 132 in the frame of the machine, and this sleeve is provided with a lug 133 adapted to engage a corresponding lug on a sleeve 134 which is fixed on the rock shaft. The rock shaft is normally maintained in the position indicated in Fig. 1 by the action of a spring 138 acting upon a treadle 137 which is connected by means of a link 136 with an arm 135 secured to the rock shaft (Fig. 4). The spring acts to hold the treadle against a stop 137^a, and to thus maintain the shaft 131 in the position indicated. With the shaft in this position, the lug 133 on the sleeve 130 engages the lug 134 and supports the arm 129 in the position indicated, so that the forked wedge 127 is held in proper position between the collars 123 and 126 to maintain the driving plate 110 midway between the friction plates 111 and 112.

When the sewing mechanism is to be thrown into operation the operator presses the treadle 137 thereby rocking the shaft 131 so that the lug on the sleeve 134 disengages the lug 133 on the sleeve 130 allowing the arm 129 and the wedge 127 which is supported thereby to fall. The spring 122 now moves the driving pulley to engage the driving plate 110 with the friction plate 111 thus connecting the driver with the sewing mechanism. The sewing mechanism will continue in operation so long as the treadle 137 is depressed. When the treadle is released the spring 138 will return the treadle to its upward position against the stop 137^a thus rocking the shaft 131 and operating the sleeve 130 and arm 128 to raise the wedge 127 to the position indicated in Fig. 1. This movement of the wedge shifts the driving plate into mid-position, thus throwing the sewing mechanism out of operation.

When the bobbin changing mechanism is to be thrown into operation the wedge 127 is forced upward from the position indicated in Fig. 1, thus forcing the collar 123 to the right and operating the rod 119 to shift the driving plate 110 into engagement with the friction disk 112. This movement of the wedge 127 is effected by a treadle 145 which is connected by means of a link 144 to an arm 143 projecting from a sleeve 140 which is loosely mounted on the shaft 131. The sleeve 140 is provided with a lug 141 ar- 130

ranged to engage a similar lug on the sleeve 130 which carries the arm 129 for supporting the wedge. When the treadle 145 is depressed the sleeve 140 is rocked and the lug 141 on the sleeve engages the lug on the sleeve 130 rocking this sleeve and raising the arm 139 so that the wedge 127 is forced between the collars 126 and 123. The movement thus imparted to the collar 123 causes the driver 110 to be engaged with the friction disk 112 so that the bobbin changing mechanism is thrown into operation. The operation of the bobbin changing mechanism will continue until the wedge 127 is returned to the normal position indicated in Fig. 1, when the spring 122 will shift the driving plate 110 into mid-position. When the bobbin changing mechanism is connected with the driver, the connection should continue until the cycle of operations incident to the change of the bobbin has been completed and then the mechanism should be disconnected from the driving mechanism. In order that the bobbin changing mechanism may remain connected with the driving mechanism after it has once been connected therewith by the operator, until the changing of the bobbins has been effected and may then be disconnected from the driving mechanism without requiring the attention of the operator, means are provided for automatically performing these operations. In the construction shown, the connection between the driving mechanism and the bobbin changing mechanism is maintained by means of a pawl 147 arranged to engage teeth 146 formed on the rod 128 to which the controlling wedge 127 is secured and to retain the rod and wedge in their raised position when the wedge is raised by the depression of the treadle 145. The pawl 147 is forced yieldingly toward the rod 128 by a spring 148 and the rear end of the pawl is connected by means of a link 149 with a pin 150 mounted on the arm 62 through which the slide sleeve 55 is operated. The pin 150 plays in an elongated slot in the upper end of the link 149 so that a certain amount of lost motion between the link 149 and the arm 62 is provided for. The cam groove which imparts movements to the arm 62 is so shaped that when the bobbin changing mechanism is thrown into operation, a slight upward movement is imparted to the arm 62 which carries the pin 150 away from the lower end of the slot in the link 149 allowing the pawl 147 to swing over into engagement with the teeth 146 on the rod 128. The pawl now retains the rod 128 and wedge 127 in raised position until the group of cams 51 which operate the devices of the bobbin changing mechanism have made a complete revolution, when the arm 62 is returned to the position indicated in Fig. 1. This move-

ment of the arm brings the pin 150 against the lower end of the slot in the link 149, thus rocking the pawl 147 out of engagement with the teeth 146 on the rod 128, so that the rod and wedge 127 may fall into the position indicated in Fig. 1. When the wedge returns to this position the spring 122 acts to disengage the driving plate 110 from the friction plate 112, thus disconnecting the bobbin changing mechanism from the driving mechanism. 75

As has already been explained the sewing mechanism when thrown out of operation should be arrested in such position that the opening 18 through which the bobbins are introduced into the recess in the bobbin driver shall be in register with the lower end of the feed chute 19. In order that the sewing mechanism may be stopped in this position, an automatic stop mechanism is provided. In the construction shown this stop mechanism comprises a spring buffer adapted to be moved into the path of a lug or projection carried by the driving shaft 11 when the treadle 137 is operated to disconnect the driving mechanism and sewing mechanism. 80 As shown in Figs. 1 and 4, one of the cams 152 which is secured to the shaft 11 is provided with a stop lug 153. The spring buffer which is adapted to engage this lug comprises a cylinder 154 pivotally mounted at 151 on the frame. A plunger 155 slides in the cylinder and has a head adapted to engage the stop lug. A collar 157 on the plunger is engaged by a stiff spring 158 in the cylinder. The plunger extends down 100 through a gland 159 and is provided with a piston 160 sliding in a cylinder 161. The piston is provided with vents 162 controlled by check valves 163. Glycerin or oil is put into the cylinder 161 and owing 105 to the operation of the check valves the piston may move freely downward while its upward movement is retarded by the fluid. A tension spring 164 connecting the cylinder 154 and the frame of the machine 110 tends to swing the buffer into position beneath the stop lug, but this is prevented while the machine is in operation by a detent 165 which engages a lug 166 on the cylinder 154. The detent is pivoted on the top of a 115 rod 167 which slides vertically in the frame of the machine and rests at its lower end on an arm 168 integral with a sleeve 169 fixed on the rock shaft 131. Another arm 170 depending from the sleeve 169 is connected 120 by a link 171 with the buffer to which the link is pivoted at 172. The detent is provided with a trip arm 173 adapted to engage the stop lug 153.

The stop mechanism operates as follows:— 125 When the rock shaft 131 is rotated by depressing the treadle 137 to start the machine, the arm 170 and link 171 swing the plunger

head 156 out from the path of the stop lug and the detent 165 is lowered to a point at which the trip arm 173 is below the path of movement of the stop lug, while the detent 5 is in position opposite the lug 166 on the cylinder 154. When the treadle is released to stop the machine the buffer swings back under the influence of the spring 164 until it is arrested by the engagement of the detent 165 and the lug 166. At the same time 10 the detent is raised so as to bring the trip arm 173 into the path of movement of the stop lug. When the stop lug engages the trip arm it thereby disengages the detent 15 and the buffer immediately swings into the path of the stop lug. The latter then engages the buffer and is arrested by the yielding resistance thereof and the sewing mechanism is thus brought to rest immediately but 20 without any jar. The spring then expands gently against the resistance of the glycerin check and moves the stop lug accurately to a predetermined position.

In operating this machine it is necessary 25 only to keep a supply of full bobbins in the chute and to depress the treadle 145 as often as it is necessary to replenish the shuttle thread. The bobbins are preferably wound with an amount of thread just sufficient to 30 sew a definite number of shoes and the bobbins are therefore changed at regular intervals.

The nature and object of the invention having been set forth, and one form of mechanism in which the features of invention 35 may be embodied having been described, what is claimed is:

1. A sewing machine, having, in combination stitch forming devices including a holder for the locking thread supply, a bobbin holding magazine, and means for transferring a bobbin from the magazine to the holder, substantially as described.

2. A sewing machine, having in combination 45 stitch forming devices including a bobbin holder for the locking thread supply, means for passing a loop of needle thread about the bobbin holder, a bobbin holding magazine, and mechanism operating to remove a bobbin from the holder and to transfer a bobbin from the magazine to the holder, substantially as described.

3. A sewing machine, having in combination 55 a bobbin holder for the locking thread supply, means for passing a loop of needle thread about the bobbin holder, a bobbin holding magazine, and mechanism under the control of the operator for removing a bobbin from the holder and transferring a bobbin from the magazine to the holder, substantially as described.

4. A sewing machine, having in combination 60 a holder for the locking thread supply open at the rear, a rotary device for passing

a loop of needle thread about the holder, and 65 mechanism operating to introduce a supply of thread through the rear of the holder, substantially as described.

5. A sewing machine, having, in combination 70 a holder for the locking thread supply open at the rear, means for engaging and carrying a loop of needle thread around the holder, and mechanism operating to introduce a bobbin through the rear of the holder, substantially as described.

6. A sewing machine, having, in combination 75 stitch forming mechanism including a discoidal shuttle, a bobbin holder for the locking thread supply, and mechanism operating to remove an empty bobbin from the holder and replace it with a full bobbin, substantially as described.

7. A sewing machine, having, in combination, a device for holding a supply of thread, 80 means for passing a loop of needle thread about the holder, mechanism constructed and arranged to introduce a segregated supply of thread into the holder, and means 85 constructed and arranged to seize and draw out the free end of said thread, substantially as described.

8. A sewing machine, having, in combination, stitch forming mechanism including a device for holding a supply of thread, a tension device, mechanism constructed and arranged to introduce a segregated supply of 90 thread into the holding device with the free end in a predetermined position, and mechanism for threading the thread through the tension device, substantially as described.

9. A sewing machine, having, in combination, a bobbin holder, means for passing a loop of needle thread about the holder, a bobbin changing mechanism for changing the bobbin within the holder, and means for 95 seizing the free end of the thread extending from the bobbin and drawing it out of the holder, substantially as described.

10. A sewing machine, having, in combination, a bobbin holder, means for passing a 100 loop of needle thread about the holder, a bobbin changing mechanism for changing the bobbin within the holder, a tension device, and means for seizing the free end of the thread extending from the bobbin and threading it through the tension device, substantially as described.

11. A sewing machine, having in combination a device for holding a supply of thread, means for passing a loop of thread 110 about the holding device, and means for seizing the end of the thread supply and drawing it out of the holder, substantially as described.

12. A sewing machine, having, in combination 115 stitch forming mechanism including a shuttle, mechanism for replenishing the supply of thread in the shuttle, shuttle driv-

ing mechanism and stop mechanism operating to stop the shuttle driving mechanism in a predetermined position, substantially as described.

5 13. A sewing machine, having in combination a bobbin holder means for passing a loop of needle thread about the holder and a thread puller operating to seize the end of the bobbin thread and draw thread from the bobbin, substantially as described.

10 14. A sewing machine, having in combination a bobbin holder means for passing a loop of needle thread about the holder, a tension device, a thread pulling gripper, and mechanism for operating the gripper to seize the bobbin thread and draw off thread from the bobbin through the tension device, substantially as described.

15 15. A sewing machine, having in combination a bobbin holder, a tension device, a tension opener, a thread gripper, and mechanism operating the thread pulley to seize the bobbin thread and draw it through the tension device, substantially as described.

20 16. A sewing machine, having, in combination stitch forming mechanism including a bobbin holder for the locking thread supply, a shuttle for passing the loop of needle thread around the bobbin holder, shuttle driving mechanism, stop mechanism operating to stop the shuttle driving mechanism in a predetermined position, and mechanism for changing the bobbin in the bobbin holder, substantially as described.

25 17. A sewing machine, having, in combination, stitch forming devices including a holder for the locking thread supply about which the needle thread passes, a bobbin holding magazine, and means for separating individual bobbins from the series in the magazine and transferring them to the holder, substantially as described.

30 18. A sewing machine, having, in combination, stitch forming devices including a holder for the locking thread supply about which the needle thread passes, a guideway for a series of bobbins, and means for transferring individual bobbins from the guideway to the holder, substantially as described.

35 19. A sewing machine, having, in combination, stitch forming devices including a holder for the locking thread supply about which the needle thread passes; a guideway for a series of full bobbins, and devices for removing an empty bobbin from the holder and transferring a full bobbin from the guideway to the holder, substantially as described.

40 20. A sewing machine, having, in com-

bination, a holder for the locking thread supply provided with an opening at its rear through which the bobbin may be introduced into the holder, means for passing a loop of needle thread around the holder, mechanism for introducing a full bobbin through the opening in the rear of the holder, and means for drawing the free end of the bobbin thread through the front of the holder, substantially as described.

45 21. A sewing machine, having, in combination, a discoidal shuttle, a bobbin holder within the shuttle, a guideway for bobbins, and means for transferring bobbins from the guideway to the bobbin holder, substantially as described.

50 22. A sewing machine, having, in combination, stitch forming devices including a holder for the locking thread supply, a bobbin having means for holding the free end of the thread wound thereon, mechanism for inserting the bobbin in the holder with the free end of the bobbin thread in a predetermined position, and means for seizing the free end and pulling out the thread, substantially as described.

55 23. A sewing machine, having, in combination, a shuttle driver provided with a hollow shank, a shuttle operated by the driver, a bobbin holder within the shuttle provided with an opening registering with the opening in the shank of the driver, and means for introducing a supply of thread into a holder through the hollow shank of the driver, substantially as described.

60 24. A sewing machine, having, in combination, stitch forming devices including a bobbin holder for the locking thread supply provided with a tension device, and mechanism for introducing a wound bobbin into the holder and inserting into the tension device the severed end of the thread projecting from the bobbin.

65 25. A lock stitch sewing machine, having, in combination, stitch forming devices including a holder for the locking thread supply, mechanism acting automatically under the control of the operator to replenish the supply of thread in the holder, and means for determining the position of the stitch forming devices when the replenishing mechanism is thrown into operation.

In testimony whereof I affix my signature, in presence of two witnesses,

FARNUM F. DORSEY.
